UNITED STATES PATENT OFFICE

FRIEDRICH MÜLLER, OF VIENNA, AUSTRIA

ARRANGEMENT FOR FACILITATING THE STARTING OF INTERNAL-COMBUSTION ENGINES

Original application filed March 25, 1921, Serial No. 455,575, and in Austria November 16, 1916. Patent No. 1,570,914, dated January 26, 1926. Divided and this application filed July 15, 1925. Serial No. 43,856.

(GRANTED UNDER THE PROVISIONS OF THE ACT OF MARCH 3, 1921, 41 STAT. L., 1313)

I have filed applications as follows:

Austria, filed Nov. 16th, 1916, granted Oct. 29th, 1919, No. 80,052; France, filed July 9th, 1920, granted May 9th, 1921, No. 524,200; Germany, filed July 10th, 1920, granted April 28th, 1923, No. 377,430; Hungary, filed Sept. 25th, 1920, granted Oct. 23rd, 1923, No. 84,927; Czechoslovakia, filed Oct. 9th, 1920, granted June 25th, 1923, No. 11,097; Poland, filed Dec. 9th, 1920, not yet accepted; Belgium, filed Mar. 5th, 1921, granted May 5th, 1921, No. 294,486; Italy, filed Mar. 29th, 1921, granted June 22nd, 1923, No. 562/62; Spain, filed Mar. 30th, 1921, granted Sept. 19th, 1921, No. 77,693; Holland, filed June 21st, 1922, granted Feb. 16th, 1925, No. 12,878; Sweden, filed July 8th, 1922, not yet accepted; Switzerland, filed July 21st, 1922, granted Nov. 27th, 1922, No. 97,711; Denmark, filed Aug. 10th, 1922, granted Nov. 6th, 1923, No. 32,506; Norway, filed Jan. 8th, 1923, granted Oct. 6th, 1924, No. 40,585.

The present invention, being a division of application Serial Number 455,575, March 25, 1921, since matured into Patent No. 1,570,914, Jan. 26, 1926, relates to a method of starting internal combustion engines the working cylinder or cylinders of which are cooperating with auxiliary pumps for example with pumps for producing injection air, for producing starting air or with fuel pumps for conveying the fuel, or with cooling water pumps and the like and in which on starting on the one hand the compression resistances of the working cylinders and on the other hand the working resistances of the auxiliary pumps are entirely or partially relieved.

The invention consists in this that the cooperating working and auxiliary cylinders are brought into normal compression by means common to these cooperating cylinders for multi-cylinder engines comprising a plurality of working cylinders the invention consists in this that the working cylinders

and auxiliary pump cylinders are brought into normal operation in sequence individually or in groups.

The advantages of such a modification of the method lie, not only in the possibility of putting the engine into operation with a small quantity of starting energy, but also in the fact that the auxiliary pumps commence to work during the starting period exactly at the correct moment. It is, for instance, of importance for Diesel engines that before the first compression stroke no fuel shall reach the working cylinder, so that, when passing to the full compression, premature ignition and the reversal of the engine shaft caused thereby may be avoided. For the same reason, before the first compression stroke, no injection air should be admitted, which conveys the fuel or the remains of fuel in the nozzle into the working cylinder in a finely divided state at the wrong time. This is best effected in those cases in which the compressors serving for the production of the injection air are connected directly to the point of injection without the interposition of air vessels, by employing the starting method according to the invention, according to which the fuel pumps and the injection air compressors are to come into operation only at the start of the actual working process.

The auxiliary pumps can be uncoupled during the starting period for doing away with the working resistances by stopping the driving members, or they are put in motion at the same time as the engine by the starting means, preferably by controlling means, which put the pumps out of operation, being connected with the starting gear of the engine in such a manner that the auxiliary pumps are brought up to the normal delivery as soon as the working cylinders pass to the normal compression. If the auxiliary pumps (i. e. more particularly the air pumps for producing starting, injection and scavenging air, the fuel

pumps for conveying the operating fuel, the cooling water pumps and the like) are put in motion by the starting means simultaneously with the engine, the air or water, respectively, must be allowed to escape from the auxiliary pump cylinders, so that there may be no working resistances in them, which is effected in the simplest manner by holding open the suction or pressure valves.

10 On the drawings:

Fig. 1 is a diagrammatic layout of an engine including fuel air, and scavenging pumps together with a control embodying the features of this invention.

15 Fig. 2 is a fragmentary detail of an auxiliary cam arrangement for opening a main valve in one cylinder.

Fig. 3 is another view of the cam of Figure 2.

20 The drawing shows in Fig. 1 a constructional form with a joint air escape means for the working cylinder and the auxiliary pump cylinders by means of cocks, while Figs. 2 and 3 show another way of providing for the escape of air from the cylinders by means of auxiliary starting cams.

The working cylinder is marked 1, the injection compressor 2, the scavenging pump 3 and the fuel pump 4. For relieving the compression and working resistances in the various cylinders, controlling means are provided, which put the working cylinder 1 and the auxiliary pump cylinders 2, 3, 4 entirely or partially out of operation during starting, the arrangement being preferably such, that this control is connected with the starting gear of the motor in such a manner, that the auxiliary pumps are brought up to the normal working as soon as the working cylinders pass to the normal compression. The controlling means comprise cut-off members for the cylinders, such for instance as the cocks 5, 6, 7, 8, which are connected together by rods 9 and 10 and can be operated both by a handle 11 and by a handle 12. Starting is effected with the cocks open. As all the compression and working resistances are cut out, the engine, under the action of the starting medium, attains in a few revolutions such a speed that after closing of the cocks the flywheel 13 can overcome, not only the working strokes of the auxiliary pump cylinder, but the compression stroke of the working cylinder, thus initiating the first working process.

55 Fig. 2 is a side view in section through one of the auxiliary cylinders, from which the air escapes by opening a main valve by means of auxiliary cams. The auxiliary pump cylinder is marked 1, the valve 2 and the cam shaft 3. The valve 2 is operated in the working position by a cam 4 and in the starting position by a cam 5 as well. As will be seen from Fig. 3, the two cams lie adjacent to one another. In order that, on starting, a cam 65 roller 6 may come in contact with both cams,

the cam shaft is, for instance displaced in the axial direction. The cam 5 keeps the valve 2 open almost during an entire cycle, so that the auxiliary pump has no work to perform.

In the case of multi-cylinder engines, the passing of all the auxiliary pump cylinders to the normal working position will be effected gradually. The gradual passing to the normal working position can be brought about, either singly or in groups, one after another, with starting gear for each group or preferably with a common starting gear, i. e. first only one group of working and auxiliary pump cylinders belonging together, is started and then, one after another, either one or more groups of the remaining cylinders.

The character of the invention is not in any way altered, if one or more auxiliary pumps are not operated by the starting gear. Thus, for instance, the starting air or cooling water pumps can commence working when the engine is running. On the other hand the scavenging air pumps of two-stroke engines can be put into the running position sooner than the corresponding working cylinders, in order to obtain, with certainty, the compression pressure required for the first ignitions.

I claim as my invention:

1. In a Diesel engine, or the like, and in combination, a working cylinder, one or more associated auxiliary driven cylinders, cylinder pressure release means for said working cylinder and each said auxiliary cylinder, and means for operating the said release means to prevent the building up of excessive pressure within all of said cylinders during the initial starting operation.

2. In a Diesel engine, or the like, and in combination, a working cylinder, one or more associated auxiliary driven cylinders, cylinder pressure release means for said working cylinder and for each associated auxiliary driven cylinder, and operating means common to the said several pressure release means for simultaneously operating said pressure release means to prevent the building up of excessive pressures within all of said cylinders during the initial starting operation.

3. In a Diesel engine, or the like, and in combination, a working cylinder and one or more associated auxiliary driven cylinders, the said cylinders being associated to operatively function as a unit, cylinder pressure release means for each said working cylinder and associated auxiliary driven cylinder, and operating means common to the said several pressure release means for simultaneously operating said pressure release means to prevent the building up of excessive pressures within all of said cylinders during the initial starting operation.

4. In a Diesel engine, or the like, and in

combination, a working cylinder, and air pump cylinder, and a fuel pump cylinder, the several cylinders being associated to operatively function as a unit, a pressure release valve for each of said cylinders, and common means for operating said pressure release valve to prevent the building up of excessive pressures within all of said cylinders during the initial starting operation.

10 In witness whereof I have hereunto signed my name.

FRIEDRICH MÜLLER.
